UNITED STATES PATENT OFFICE.

HEINRICH KOPPERS, OF ESSEN-ON-THE-RUHR, GERMANY, ASSIGNOR, BY MESNE ASSIGNMENTS, TO THE KOPPERS COMPANY, A CORPORATION OF PENNSYLVANIA.

PROCESS FOR INCREASING THE EFFICIENCY AND THE YIELD OF AMMONIA IN GAS-PRODUCERS.

1,360,117

Specification of Letters Patent. Patented Nov. 23, 1920.

Application filed September 9, 1914. Serial No. 860,884.

To all whom it may concern:

Be it known that I, HEINRICH KOPPERS, engineer, residing at Essen-on-the-Ruhr, 29 Moltkestrasse, Germany, have invented certain new and useful Processes for Increasing the Efficiency and the Yield of Ammonia in Gas-Producers, of which the following is a specification.

This invention relates to an improved process for introducing a combustible gas into gas producers, and causing said gas to burn in the charge of the producer shaft.

In the production of gas from all kinds of combustibles, the efficiency and the yield of ammonia is increased, by the introduction of a combustible gas, which by effecting an internal combustion, will correspondingly increase the temperature of the zone of reaction or conversion. In carrying out this operation, two considerations must be borne in mind. The gas and the air supplied from below the grate must commingle at, or in the immediate vicinity of the zone of conversion, so as to avoid useless combustion and danger of explosion. On the other hand, the gas and air carried to said zone of conversion, must be so atomized that the combustion will be actually restricted to said zone.

By my invention the above conditions are effectively fulfilled. According to the same, air passes from below through the apertures of a rotatable grate, while the gas flows along radial channels of the grate between said apertures. These channels are fed from a common gas supply pipe, so that the gas and air will not meet until reaching the upper surface of the conical grate, where they will be discharged in the form of a spray. The temperature of the zone of conversion is always so high that the air and gas will be ignited, and will burn at a ratio corresponding to the proportions of air and gas in the mixture, so that any danger of explosion is obviated. Owing to the uniform regulation of the combustion, the intended heating of the zone of conversion is thus carried out in an efficient manner.

In the accompanying drawing:

Figure 1 is a vertical central section of

part of a gas producer adapted for carrying my invention into effect, and

Fig. 2 a plan of the grate.

In the shaft 10 of the producer is arranged the rotary grate 11, which is sealed against the casing 13 by means of the hydraulic seal 12. Into the casing 13 air and steam mixed, are introduced by pipe 14 and enter the charge by the holes 15 of the grate 16. Between the holes 15 radial channels 17 are arranged, which communicate with the ring channel 18, the latter being connected with the central pipe 19. A hydraulic seal 20 allows the pipe 19 to turn around the fixed gas conduit 21. To maintain this inner seal 20 constantly filled in a simple manner a pipe 22 connects it with the outer seal 12. The channels 17 have apertures 23 by which the gas is introduced into the charge in a fine division and in proximity to the air. The steam introduced into the producer is required for the primary production of ammonia. By the introduction of a combustible gas along with the steam and the burning of said gas in the producer, the temperature of the conversion zone is increased and secondary decomposition of the ammonia is prevented. In this way the supply of gas is effected in the manner desired.

What I claim as my invention and desire to secure by Letters Patent of the United States is:

1. A process for increasing the efficiency and the yield of ammonia in gas-producers consisting in an internal heating of the charge by introducing a combustible gas and causing its combustion in the interior of the charge, the gas and air of combustion being introduced in atomized jets distributed in close proximity to each other.

2. A process for increasing the efficiency and the yield of ammonia in gas-producers consisting in an internal heating of the charge by introducing a combustible gas and causing its combustion in the interior of the charge, the gas and air of combustion being introduced in atomized jets distributed in close proximity to each other and flowing in a whirling manner into a zone of conversion within the interior of the charge.

3. The process of increasing the efficiency and the yield of ammonia in gas-producers, which consists in introducing a combustible gas into the producer with the steam required for the primary production of ammonia, and burning said combustible gas inside the producer, thereby increasing the

temperature of the conversion zone and preventing secondary decomposition of the ammonia.

HEINRICH KOPPERS.
